CANNING APPARATUS.

1,418,574.

Specification of Letters Patent. Patented June 6, 1922.

Application filed March 28, 1921. Serial No. 456,147.

To all whom it may concern:

Be it known that we, SIMES T. HOYT and JOHN S. NAPIER, citizens of the United States, residing at and whose post-office address is Honolulu, Territory of Hawaii, have invented certain new and useful Improvements in Canning Apparatus; and they do hereby declare the following to be a full, clear, and exact description of the invention, 10 such as will enable others skilled in the art to which it appertains to make and use the same.

This invention relates to canning apparatus, and particularly to a cooker or cooler 15 construction, of a double-track type, wherein in the cans containing the foodstuffs are adapted to be continuously advanced therethrough, preferably from the bottom to the top thereof, and during their course of 20 travel carried backward and forward through the apparatus and successively elevated from one plane to another by a single length of specially designed chain conveyor traveling between the tracks, said 25 chain having laterally disposed arms engaging the cans to carry them along with the movement of the conveyor, the cans being engaged at all times by the laterally disposed arms, both during the travel of said 30 cans along the different plane levels, and also as said cans are elevated from one plane to the next higher plane, the apparatus being so constructed at these transfer points to cooperate with the conveyor chain in a novel 35 manner, to perform this latter function.

In the process of canning fruit, vegetables and other foods, it is the usual practice to seal the articles in cans, and by the application 40 of heat effect the sterilization of cooking of the materials to prevent subsequent spoilage, the length of time required and the proper temperature necessary varying with the different kinds of foods.

Among the devices generally used for 45 cooking are the hot water open tub type, the closed retort compartment, cooking under pressure at a temperature above 212 F., and various types of continuous cookers, in which each can is passed through a chamber 50 of hot water or steam, or both, at the desired temperature. In this last type of cooker, the course of the cans through the machine must be such that sufficient time is allowed in the hot chamber to insure the

necessary heating of the contents of the cans 55 and the sufficient cooking thereof.

The cooking machines which have been designed for continuous operation, in which the contents of the cans have been agitated, and a rapid distribution of heat through 60 them brought about thereby, have heretofore proved disadvantageous from a structural and practical standpoint, for the reason that said cans are frequently injured, and the apparatus jammed, resulting in undesirable 65 delays, and those in which the contents of the cans are not agitated require a much longer period of time to accomplish the same degree of heating, and their output is therefore less than would be the case 70 if adequate mixing of the contents could be brought about during the heating period in a continuous manner without the inherent disadvantages incident to the previous types of machines of this character. 75

It is likewise important to also manipulate the cans as they come from the cooker so as to effectively and efficiently cool the same without injury to the cans or their contents, or to the apparatus, and without 80 such an apparatus the handling of the hot cans coming from said cooker is oftentimes attended with various difficulties. If the cans are cooled simply by stacking them up with more or less access to air, a large 85 amount of floor space and extra handling is required, and if they are stacked in dense piles, at too high a temperature, the cooking of the contents may continue, on the principle of the fireless cooker, to their serious 90 detriment.

It has therefore been found to be of great advantage to cool the cans by a process operating upon them immediately after their discharge from the cooker, in such a way 95 that their temperature will be reduced to the point where they can be conveniently handled, immediately labeled and packed, and thereby overcome the various difficulties incident to this artificial cooling, which has heretofore been practiced in a more or less 100 ineffective manner. It has therefore been found preferable, and very desirable from a practical standpoint, to cause the cans during the cooling process to travel separately 105 and successively as in the cooker construction, for the necessary length of time through a cooling medium, and the present

invention is equally well adapted for such use, the same general arrangement, conveyor construction, and mode of operation being identical in both cases, it only being necessary to substitute a cooling medium, where a cooler is desired, requiring simply a duplication of the cooking apparatus with certain alterations, as above indicated, said apparatus being so placed with respect to each other that the operation will be continuous from one to the other.

The principal object of the invention, which is as desirable in connection with a cooker as with a cooler, is the provision of a machine of the continuous type, allowing a constant intake of cans of uncooked food-stuffs and a correspondingly constant output of cans of cooked food, with respect to the cooker, and, likewise, a constant intake of heated cans and an output of cooled cans, when applied to the cooler, at the same time causing a continuous agitation of the contents of said cans, thus shortening the time of cooking or cooling thereof, and thus increasing the capacity of the machine, the whole operation being carried on by the use of a single conveyor chain, without injury to the cans or their contents and without loss of time due to the constant stoppage of the machine, as in the common types of so-called continuously operated apparatus of a similar character.

These advantages are secured by causing the cans to travel through the machine by rolling on tracks so arranged that said cans will move horizontally for a distance, substantially the length of the apparatus, whereupon they are elevated to a slightly higher level and roll horizontally in the return direction and again elevated, this rolling of the cans from one end of the machine to the other, at constantly increasing elevations, being continued until they are ultimately discharged, having been exposed during their period of passage through said machine to the action of hot water or steam, or a cooling medium, as the case may be.

The cans are caused to move along these tracks by means of a single moving endless chain provided with a series of lateral projections, which in addition to moving the cans along the various levels assist in elevating them from one plane to the next higher plane, said mechanism of tracks and chain, with the auxiliary sprockets, guides, etc., being mounted inside a housing or the like supplied with the necessary heating or cooling medium or media. Thus by the improved means for continuously rolling the cans, their contents are continually agitated, allowing the heating or cooling medium to effect a thorough cooking or cooling in a very short time.

By reason of the large number of cans capable of being handled by the machine,

their rapid and continuous motion, and the general design of the apparatus, there is accomplished a great economy in space and time, without injury to the cans or their contents, as is oftentimes the case in the usual so-called endless conveyor apparatus, where a series of endless chains is employed and the cans are dropped from one flight to the other, oftentimes resulting in the further disadvantages of jamming or injury to the apparatus and the frequent stoppage thereof.

The preferred embodiment of the invention is illustrated in the accompanying drawings, in which—

Fig. 1 is a fragmentary view in side elevation, showing the framework of the apparatus and its cooperating mechanism.

Fig. 2 is an enlarged view in side elevation of one end thereof, more clearly illustrating the essential features of the invention and the operating mechanism.

Fig. 3 is an enlarged detailed view, partly in section and partly in elevation, of the means for elevating the cans from one flight to the next higher flight, taken in line 3—3 of Fig. 1.

Fig. 4 is a sectional view on line 4—4 of Fig. 3, and

Figs. 5 and 6 illustrate modifications, whereby the apparatus may be adapted to either the cooker or cooler constructions.

Referring to the drawings in detail, with particular reference to Fig. 1, the invention comprises a substantially rectangular framework consisting of a base including a pair of connected main side sills 1, vertically disposed corner members 2, and oppositely disposed, vertically arranged intermediate members 3, the lower ends of said members being appropriately secured to the longitudinal sills or base 1. Extending transversely of the framework, and having their ends secured to said corner and intermediate members, are a series of vertically spaced, horizontally disposed cross-bars or supports 2' and 3', upon which are supported within the corner members 2 and intermediate members 3, a series of parallel arranged tracks 4, disposed at different levels, there being two pairs of tracks to each level, forming a double track-way arrangement, the corner members 2 being sufficiently spaced transversely of the framework to permit this double track-way arrangement, as clearly shown in Fig. 3. Each track is preferably of L-shape in cross section, forming a supporting flange for the cans, and also a vertically disposed flange to prevent the lateral displacement of the cans during their course along the track.

The herein described framework may be of any size, and the parallel arranged track-ways or flights may be of any length and number, but it has been found preferable

to limit the same to ten flights or runs of substantially 18 feet in length, which will allow the rolling can a path of at least 180 feet.

- 5 At one end of the framework is secured a pair of inclined supports 5, having mounted thereon the operating mechanism for the apparatus, to be hereinafter more fully described, the base 1 being provided with end 70 extensions 6 for attaching thereto the lower ends of the inclined supports 5, the upper ends of said supports being secured in any convenient manner to the adjacent upper corners of the framework. Secured to the 75 corner members 2, adjacent the ends of the track-ways 4, and adapted to cooperate therewith, are semi-circular housings or guides comprising disc-like end plates 7, having their curved outer edges connected by semi-circular plates 8, each forming substantially an inclosed housing for retaining 80 and guiding the cans as they are conveyed upwardly from one flight to the other, in a manner to be hereinafter more fully described. The disc-like plates 7 of each housing are provided with central openings forming bearings for a shaft 9, carrying a sprocket 10, around which a conveyor chain 11 is adapted to run from end to end of the 85 machine during its continuous course therethrough, the said chain 11 being provided with laterally disposed arms 12 for engaging and causing the movement of the cans 13 along the tracks 4. It is to be here understood that the conveyor chain travels between the double track-ways, and that the laterally disposed arms project over said tracks to engage the cans thereon. The chain 11 preferably moves in a direction to 90 convey the cans from the bottom of the apparatus to the top thereof and the movements of said chain are controlled by a sprocket 14, secured to a shaft 15, journalled on the upper ends of the inclined supports 95 5. This shaft 15 also carries a gear wheel 16, meshing with a pinion 17, keyed to the shaft supporting the driving pulley 18, also located on the supports 5, immediately below the mounting for the sprocket 14 and 100 gear wheel 16.

As hereinbefore stated, the conveyor chain 11 is of a single continuous length, and in order to compensate for the slackening of said chain, owing to wear or other conditions, 105 there is mounted in the circuit of said chain, and preferably on the supports 5, a slack adjusting device 19, which is substantially a sprocket equipped with a proper mounting, slidably positioned on the supports 5, in a manner to be hereinafter more fully described. As the chain passes over the driving sprocket 14, and around the slack adjusting sprocket 19, the circuit is completed 110 by the chain finally passing around the sprocket 20, mounted on the base extensions 115 65 of the supports 5, and secured to the framework, at which point said chain is conducted and guided into the entrance or receiving end of the apparatus, where the cans containing the foodstuff to be cooked or cooled are conveyed by an inclined track 21, having mounted thereon an automatic gate arrangement 22 for controlling the entrance of the cans, successively, to the apparatus, where they are engaged by the laterally disposed arms 12 of the conveyor chain 11 and conducted 120 backward and forward through said apparatus, preferably from the bottom to the top thereof, by way of the successive flights, the chain not only being adapted to convey the cans along the track levels but also to assist 125 in elevating said cans from one plane to another, cooperating at the various points of transfer with the semi-cylindrical housing there provided for the purpose, the details of which will be described more fully hereinafter.

As the cans reach the top of the apparatus and pass out therefrom they finally arrive at the inclined delivery chute 23, which is similar in construction to the 90 double-track arrangement heretofore described, the inner rails of each track-way of the chute 23 being cut away as at 24 sufficiently to allow the laterally disposed arms 12 of the conveyor chain 11 to pass through 95 in its continuous course around and through the apparatus, the cans rolling by gravity from the delivery chute 23 to the desired point for the next operation. If the herein described apparatus is to be used as a cooker, 100 the track 23 will deliver the cans to a similar apparatus wherein they will be put through the cooling process, and as the cans are then delivered from the cooler by the track corresponding to 23, they will be conducted to the proper location, where the necessary labels are applied and the cans packed for shipment.

As hereinbefore stated, the particular novelty of this invention, over similar apparatus well known in the art, is that the cans are conveyed through the cooking or cooling medium by a single length of a continuously operated conveyor chain, the cans moving preferably from the bottom to the 115 top of the apparatus, being elevated from one flight to another, the laterally disposed arms of the conveyor chain not only adapted to move the cans along the level track-ways of the various flights, but at all times 120 controlling the movement of said cans even while they are being transferred to the successive flights. This elevating of the cans at the transfer points at the ends of the track-ways is accomplished by a novel arrangement of semi-cylindrical housing, shown in detail in Figs. 3 and 4. It will be 125 here noted that shaft 9, journalled in the disc-like end plates 7, has mounted therein intermediate its ends a sprocket 10, around 130

which the conveyor chain is conducted. Also carried by said shaft 9, and disposed at each side of the sprocket 10, are rollers 25 provided with end flanges 26, the rollers 25 being of such length and the flanges 26 thereof being so spaced as to allow for the rotation of the cans 13 around the rollers 25, and permitting them to be maintained in proper position, being confined against lateral movement by the end flanges 26 of said rollers 25 during the elevation of the cans from one track to the other.

Cooperating with the rollers 25 is a semi-cylindrical guide or retaining plate 8, arranged concentric with said rollers and properly spaced therefrom to permit the passage of the cans between the roller and said retaining plate, as said cans are pushed therebetween by the laterally disposed arms 12 of the conveyor chain. By this arrangement the cans are maintained in contact with the conveyor at all times, and in their same relative position with respect thereto and to each other, from the time they enter the apparatus until they are finally discharged upon the completion of the cooking or cooling process. This is highly important and a material advantage over present constructions of apparatus of this type, whereby the cans are dropped from one flight to another, leaving one conveyor to be subsequently picked up by another conveyor, this same operation not only occurring once in the course of the cans through these previous constructions, but each time a can is dropped to a different flight or elevation, and, consequently, the more flights employed the more danger there is of jamming the apparatus and the denting of the cans, which in time will result, also, in injury to the apparatus, necessitating the frequent stopping thereof to make the necessary repairs.

In order to bridge the space between the ends of the track-ways, at the upper outlet 45 end of the apparatus, and that section of track-way adjacent the discharge chute, there is provided a pair of flanged rollers 27 acting in a similar manner to the flanged rollers 25, hereinbefore described, these rollers 27, however, being merely for the purpose of conveying the cans from the horizontal track-ways to the angularly disposed track-ways and at the same time preventing any lateral displacement thereof.

It will be perfectly obvious that where a long, single, continuous length of chain is employed, necessary means will have to be provided for taking care of the slack in said chain, which, from time to time might develop, due to wear or other conditions. For this purpose there is provided a slack adjusting sprocket 19, secured to a shaft 28, having its ends rotatably supported in bearings 29, which are in turn slidably positioned in a pair of guide members 30, secured to the

diagonal supports 5. Each of the sliding bearings 29 is provided with a screw 31 engaging threads in an upstanding end portion 32 of the guide member 30, the outer ends of the screw 31 being equipped with a socket fitting 33 in which may be inserted a rod or bar for rotating said screw and thereby adjusting the sprocket and its supporting bearings longitudinally of the angularly disposed members 5, and thus tightening or slackening the conveyor chain as conditions may require.

The particular form of gate, designated as 22, which forms the subject matter of a co-pending application, Ser. No. 448,716 has 80 been found to be most effective for the successive feeding of the cans into the entrance of the apparatus, so that there will be no jamming or piling up of said cans at this point, comprises a U-shaped member 34 having its free ends pivoted at 35 to one of the supports of the inclined track-way 21. The closed end of the U-shaped member 34 is provided with an end stop having a straight downwardly extending portion 36 and 85 curved upper end 37, the portion 36 temporarily checking the cans in their downward flight and preventing their jumping over the top of the preceding cans and the curved upper end 37 preventing said cans 90 from jumping over the gate. The inclined track-way 21 is of the same general double track-way construction, above referred to, each track being L-shaped in cross-section as the tracks previously described, said inclined track-ways at their lower ends having their can-supporting flanges cut away to permit the cans to drop successively off of the ends thereof after being checked by the stop 36 of the gate 22, thus allowing only 100 one can at a time to be deposited on the lower track-ways of the apparatus in a position to be picked up by the laterally disposed arms 105 110 12 of the conveyor chain 11.

As hereinbefore stated, the general form 110 of apparatus herein described is equally well adapted as a cooker or a cooler, it only being necessary to provide a different means of inclosing the framework. The modification shown in Fig. 5 is a fragmentary sectional view, illustrating the mechanism as applied 115 to a cooker construction. In so using the apparatus, the framework will be inclosed in a housing 38 in order to retain therewithin the cooking medium, preferably steam, admitted thereto by pipes or the like 39, disposed along the bottom of the apparatus. When the device is to be used for a cooler, the inclosure 38 is dispensed with and in its place is substituted an openwork structure 120 125 for the circulation of air, and an arrangement of deflecting baffle plates 41 for the purpose of confining and directing to the cans the cooling fluid, such as water or the like, which is adapted to be sprayed down- 130

- wardly from the top of the apparatus through suitable pipes, not shown. In both constructions, however, the lowest track-ways, or extreme bottom flight, is inclosed 5 in a trough 40 in order to provide a receptacle for containing either hot or cold water, as the case may be, according to whether the apparatus is to be used for a cooker or a cooler, through which water the cans are 10 first conducted as they enter the apparatus to cause the initial heating or cooling of the foodstuffs contained in the cans.
- In order to prevent any tendency of the cans to float to the surface of the water in 15 the trough 40, a series of longitudinally arranged track-like members 42 are positioned in said trough 40 immediately above the track-ways of the bottom flight supporting the cans.
- 20 Of course means are provided for maintaining the proper level of the water in the trough 40 so that there will be no danger of flooding or overflowing of the water therefrom.
- 25 The moving of the cans through the apparatus from the bottom to the top thereof is particularly desirable when said apparatus is used as a cooler, as it makes use of the well known and highly advantageous 30 counter-flow principle of heat exchange, which is not possible with the usual form of apparatus, wherein the cans are caused to move from the top to the bottom thereof. With the present cooler construction, herein 35 described, the cooling water or similar fluid being sprayed downwardly from the top of the apparatus, the coldest water first comes in contact with the most nearly cooled cans, completing the cooling process, and the most 40 highly heated cans, coming immediately from the cooker, are brought into contact with the water which has already been in contact with cans at lower temperatures, so that the water which flows away from the 45 apparatus is heated to a high temperature and its cooling properties have been most effectively utilized, resulting in great economy in the amount of water used, combined with efficient cooling.
- 50 From the foregoing description, it will be apparent that applicants have provided a very simple yet efficient apparatus whereby a continuous series of cans may be conducted by gravity into the apparatus, conveyed 55 therethrough by way of a series of flights, and discharged from said apparatus, also by gravity, the cans being rolled continuously, preferably from the bottom to the top of the apparatus, said operations being accomplished 60 by a single endless conveyor, means being provided on the conveyor for maintaining contact with each individual can at all times while the cans are being moved along the respective flights, and also during 65 the elevating of said cans from one flight to the next higher flight, all of which has been found, from practical use and operation of the apparatus, to be a decided improvement over previous constructions of so-called continuously operated apparatus, wherein a 70 separate endless chain is used in connection with each flight, and the cans are caused to move downwardly from the top to the bottom of the apparatus.
- 75 What we claim is:
1. In an apparatus for cooking or cooling foodstuffs in cans, the combination with a series of flights, each flight comprising a pair of track-ways whereby a double row of cans is progressively elevated, of means for admitting the cans at the bottom of the apparatus, means for discharging said cans at the top of the apparatus, an endless chain conveyor mounted to travel between said pairs of track-ways, laterally disposed projections carried by said chain for engaging the cans on both track-ways to cause the movement of the cans thereon, and means carried at the ends of the track-ways adapted to cooperate with said chain to cause the elevation of said cans from the track-way of one plane to the track-way of the next higher plane.
- 80 2. In an apparatus for cooking or cooling foodstuffs in cans, the combination with a series of flights, each flight comprising a pair of track-ways whereby a double row of cans is progressively elevated, of means for admitting the cans at the bottom of the apparatus, means for discharging said cans at the 85 top of the apparatus, an endless chain conveyor mounted to travel between said pairs of track-ways, laterally disposed projections carried by said chain for engaging the cans thereon, and inclosed housing connecting the 90 adjacent ends of said track-ways through which the chain passes and adapted to cooperate therewith to cause the elevation of said cans from the track-ways of one plane to the track-ways of the next higher plane.
- 95 3. In an apparatus for cooking or cooling foodstuffs in cans, the combination with a series of flights, each flight comprising a pair of track-ways whereby a double row of cans is progressively elevated, of means for admitting the cans at the bottom of the apparatus, means for discharging said cans at the 100 top of the apparatus, an endless chain conveyor mounted to travel between said pairs of track-ways, laterally disposed projections carried by said chain for engaging the cans thereon, and hollow, substantially cylindrical shaped housings connecting the adjacent ends of said track-ways through which the chain passes, and rollers mounted 105 within said housings around which the cans are caused to roll by the movement of said chain to elevate said cans from the track-ways of one plane to the track-ways of the 110 next higher plane.
- 115 4. In an apparatus for cooking or cooling foodstuffs in cans, the combination with a series of flights, each flight comprising a pair of track-ways whereby a double row of cans is progressively elevated, of means for admitting the cans at the bottom of the apparatus, means for discharging said cans at the 120 top of the apparatus, an endless chain conveyor mounted to travel between said pairs of track-ways, laterally disposed projections carried by said chain for engaging the cans thereon, hollow, substantially cylindrical shaped housings connecting the adjacent ends of said track-ways through which the chain passes, and rollers mounted 125 within said housings around which the cans are caused to roll by the movement of said chain to elevate said cans from the track-ways of one plane to the track-ways of the next higher plane.

4. In an apparatus for cooking or cooling foodstuffs in cans, the combination with a series of flights, each flight comprising a pair of track-ways whereby a double row of 5 cans is progressively elevated, of means for admitting the cans at the bottom of the apparatus, means for discharging said cans at the top of the apparatus, an endless chain conveyor mounted to travel between said 10 pairs of track-ways, laterally disposed projections carried by said chain for engaging the cans on both track-ways to cause the movement of the cans thereon, hollow, semi-cylindrical housings, connecting in pairs the 15 adjacent ends of said vertically spaced track-ways, a shaft concentrically mounted within each housing, rotatable means carried midway of said shaft adapted to support and around which the chain is conducted, and a 20 flanged roller also rotatably mounted on said shaft to each side of said chain-supporting means, around which the cans from the track-ways are caused to roll by the movement of said chain to elevate said cans from 25 the track-ways of one plane to the track-ways of the next higher plane.
5. In an apparatus for cooking or cooling foodstuffs in cans, the combination with a framework of a series of vertically spaced, 30 horizontally arranged, superimposed track-ways arranged in pairs, supported within said framework, along which the cans containing the foodstuffs under treatment are adapted to roll from the bottom to the 35 top of the apparatus, inclined track-ways positioned at the entrance of said apparatus, means cooperating with the inclined track-ways for successively admitting said cans on to the lowermost track-ways at the bottom 40 of said framework, inclined track-ways at the top of said framework for discharging the cans, an endless chain conveyor mounted to travel between said track-ways, laterally disposed projecting arms carried by 45 said chain, extending over both tracks of the track-ways, for engaging the cans as they enter the framework, moving them along said track-ways, and also conducting them to the inclined discharging track-ways, in a 50 continuous manner, and substantially closed housings connecting the adjacent ends of said track-ways within the framework, through which the chain in its course is adapted to pass and cooperate therewith to 55 cause the elevation of said cans from the track-ways of one plane to the track-ways of the next higher plane.
6. In an apparatus for cooking or cooling foodstuffs in cans, the combination with a 60 framework of a series of vertically spaced, horizontally arranged, superimposed track-ways arranged in pairs, supported within said framework, along which the cans containing the foodstuffs under treatment are adapted to roll from the bottom to the top 65 of the apparatus, inclined trackways positioned at the entrance of said apparatus, means cooperating with the inclined track-ways for successively admitting said cans on to the lowermost track-ways at the bottom 70 of said framework, inclined track-ways at the top of said framework for discharging the cans, an endless chain conveyor mounted to travel between said track-ways, laterally disposed projecting arms carried by 75 said chain, extending over both tracks of the trackways, for engaging the cans as they enter the framework, moving them along said track-ways, and also conducting them to the inclined discharging track-ways, in a continuous manner; substantially hollow, cylindrical housings connecting the adjacent ends of said track-ways within the framework, through which the chain in its course is adapted to pass, and rollers mounted within said housings around which the cans are caused to roll by the movement of said chain to elevate said cans from the track-ways of one plane to the track-ways of the next higher plane.
7. In an apparatus for cooking or cooling foodstuffs in cans, the combination with a framework of a series of vertically spaced, horizontally arranged, superimposed track-ways arranged in pairs, supported within 90 said framework, along which the cans containing the foodstuffs under treatment are adapted to roll from the bottom to the top of the apparatus, inclined track-ways positioned at the entrance of said apparatus, means cooperating with the inclined track-ways for successively admitting said cans on to the lowermost track-ways at the bottom 95 of said framework, inclined track-ways at the top of said framework for discharging the cans, an endless chain conveyor mounted to travel between said track-ways, laterally disposed projecting arms carried by 100 said chain, extending over both tracks of the track-ways, for engaging the cans as they enter the framework, moving them along said track-ways, and also conducting them to the inclined discharging track-ways, in a continuous manner; hollow, semi-cylindrical housings connecting in pairs the adjacent ends of said horizontally arranged, vertically spaced track-ways, a shaft concentrically mounted within each housing, means carried midway of said shaft adapted to support and around which the chain is conducted, a flanged roller rotatably mounted 110 on said shaft to each side of said chain-supporting means, around which the cans from the track-ways are caused to roll by the movement of said chains to elevate said cans from the track-ways of one plane to the track-ways of the next higher plane, and flanged rollers mounted at the discharge end 115 120 125

of the uppermost horizontal track-ways over which the cans are conducted by the chain to the inclined discharging track-ways.

8. In an apparatus for cooking or cooling foodstuffs in cans, the combination with a framework of a series of vertically spaced, horizontally arranged, superimposed track-ways arranged in pairs, supported within said framework, along which the cans containing the foodstuffs under treatment are adapted to roll from the bottom to the top of the apparatus, inclined track-ways positioned at the entrance of said apparatus, an automatic gate cooperating with the inclined track-ways for successively admitting said cans on to the lowermost track-ways at the bottom of said framework, inclined track-ways at the top of said framework for discharging the cans, an endless chain conveyor mounted to travel between said track-ways, oppositely disposed, laterally projecting
- arms carried by said chain, extending over both tracks of the track-ways, for engaging the cans as they enter the framework, moving them along said track-ways, and also 25 conducting them to the inclined discharging track-ways, in a continuous manner, and substantially closed housings connecting the adjacent ends of said track-ways within the framework, through which the chain in its 30 course is adapted to pass and cooperate therewith to cause the elevation of said cans from the track-ways of one plane to the track-ways of the next higher plane, means for operating said chain, and means for 35 regulating the tension of said chain, both carried by the framework.

In testimony whereof we affix our signatures.

SIMES T. HOYT.
JOHN S. NAPIER.
